COMBINED WASHER AND DRIER

Carl E. Lang, San Francisco, Calif.

Application February 2, 1935, Serial No. 4,708

1 Claim. (Cl. 68—210)

My invention relates to improvements in combined washers and driers, and it consists of the combinations, constructions and arrangements hereinafter described and claimed.

5 In the standard washing machine a mechanical clothes agitator is used for moving the clothes in the washing liquid. I have found that when mechanical means is used the clothes often will be torn.

10 The principal object of the present invention is to provide a combined clothes washer and drier in which the washing fluid itself is caused to flow in such a manner as to be forced through the clothes and thus clean them without subjecting 15 the clothes to a mechanical agitator. In this way the wear on the clothes during the washing operation is reduced to a minimum.

15 A further disadvantage of the standard washing machines using a mechanical agitator lies in the fact that the agitator projects above the bottom of the tub, and the shaft of the agitator extends through a packing gland in the tub bottom. Very often this packing gland leaks. Furthermore the cost of the washing machine is increased because of the necessity of placing a packing gland in the tub bottom which will be leak-proof.

20 In the present invention I mount a clothes basket or container in the tub, and I suspend the clothes basket from the top of the washing machine by means of a frame and motion is imparted to the clothes basket by rotating the frame.

25 The clothes basket may be tilted so that it may be filled or emptied from the top of the machine with little effort.

30 The means for forcing the washing fluid through the clothes comprises means for causing the fluid to revolve in the tub with means for restricting the passage of the fluid at a certain 35 place for forcing the fluid into the perforated basket. The fluid entering the basket is forced through the clothes, and thus cleans them.

35 Other objects and advantages will appear in the following specification, and the novel features 40 of the device will be particularly pointed out in the appended claim.

45 My invention is illustrated in the accompanying drawing forming a part of this application, in which

50 Figure 1 is a vertical section through the washing and drying machine, parts being shown in elevation; and

55 Figure 2 is a horizontal section taken substantially along the line 2—2 of Figure 1.

55 In carrying out my invention I provide a wash-

ing machine and clothes drier having a storage compartment A and washing and drying compartment or tub B. The compartment or tub B is placed above the compartment A and both are supported by any suitable means such as by 5 legs 1.

Within the compartment B I dispose a frame 2, and this frame is fixedly carried by a rotatable shaft 3. The shaft in turn is mounted in bearings 4, and is rotated by an electric motor 5, or 10 other suitable power source through the means of a belt and pulley mechanism 6, or other suitable operating mechanism.

15 Within the frame 2 I pivotally dispose a perforated basket 7, the basket or container being pivotally mounted on the frame at 8. This basket may be tilted into the dotted line position shown in Figure 1, for ease of loading and unloading the basket. A cover 9 is placed over the top of the basket, and if desired this cover may 20 be formed of two sections 9a and 9b, hinged at 10 so that the cover can be more readily removed through the open top 11 of the compartment B.

25 When the basket 7 is swung into the full line position shown in Figures 1 and 2, the cover 9 is secured to the top cross piece 12 of the frame 2 by means of projections 13. The projections 13 are carried by the top 9, and are removably secured to the top piece 12 by bolts 14. The bolts 14 are slidably mounted in elongated bearings 14' 30 and have their ends removably disposed in a keeper 14''. The projections 13 are received between the bearings 14' and the keepers 14''. Figure 1 shows the bearings 14' and keepers 14'' supported by the frame 2. The basket is now in 35 operative position, and will be rotated by the motor 5.

40 I will now describe the means for circulating the washing fluid in the compartment B and for causing this fluid to be forced into the basket 7 and through the clothes for washing purposes. In Figure 2 I show a fluid diverting partition 15 arcuate in shape and disposed in the compartment B so as to form a restricted passageway at 16 between the partition and the container or basket 7. The partition 15 preferably extends 45 throughout the height of the compartment B and can be arranged vertically. In the drawing I have shown the partition as extending vertically in the compartment B. The curved part 50 of the partition extends inwardly into close proximity to the container.

55 The frame 2 pivotally carries vanes 17, and these vanes are positively swung so as to follow the inner surface of the compartment B. Any 55

means for thus swinging the vanes may be used and I have shown one mechanism for accomplishing this in Figure 2. Each vane carries a quadrant 18 which meshes with a rack 19 on a 5 spring pressed rod 20, slidably carried in brackets 2' supported by the frame 2. The inner end of each rod carries a roller 21, that rides on a cam 22. A spring 25 mounted on each rod, bears against a collar 25' secured to the rod and 10 against one of the brackets 2' for yieldingly moving the rod toward the cam. The cam has a high spot 23 which conforms with the shape of the partition 15 so that the vane 17 will gradually be swung from a position which is radial to the 15 center of the compartment B into a position which is substantially at right angles to the radii. In Figure 2 I have shown two vanes 17 and this figure illustrates how the vanes are swung.

The cam 22 is secured to a casting 24 that 20 houses the basket rotating mechanism, and in this way the cam is prevented from rotating. It will be seen that in the operation of the device as soon as the roller 21 leaves the high spot 23 of the cam 22, the spring 25 will quickly move the rod 25 20 so that the vane 17 will again be swung into a radial position. The movement of the vanes 17 will cause the fluid to circulate in the compartment B. The fluid will be forced through the narrowing passageway 16, and being restricted, will flow into the basket 7, and will force its way through the clothes.

As an aid for causing the washing fluid to move toward the center of the basket 7, I provide indentations 26 on the inside of the basket, see 35 Figure 2. These indentations in reality are portions of the perforated container wall bent inwardly and have a surface 26a extending inwardly substantially at right angles to the adjacent curved wall of the basket. This radially extending surface causes the fluid to be deflected through the wall and toward the center of the basket.

As a further aid for causing the liquid to circulate between the inner surface of the tub or 45 compartment B and the perforated container or basket 7, I provide auxiliary vanes 27 which are secured to the basket at 28. These vanes 27 extend radially from the basket 7 and act as paddles and cooperate with the vanes 17 for positively 50 circulating the fluid in the space between the vertical wall of the compartment B and the container 7.

After the washing operation the washing fluid in the compartment B may be drained into the 55 storage compartment A by means of opening a valve 29 in a pipe 30 that places the compartment B in communication with the compartment A. After all of the washing fluid has been drained into the compartment A the valve is 60 closed and rinsing fluid is added to the compartment B. The basket 7 may now be rotated in the manner already described, and this will cause the rinsing fluid to remove all of the cleaning fluid from the clothes. After the rinsing has 65 been completed the rinsing fluid may be removed from the compartment B through a discharge pipe 31 when a valve 32 normally closing this pipe is opened. It is obvious that any other means desired may be used for conveying the washing 70 fluid from the compartment B to the compartment A, and also any means may be used for releasing the rinsing fluid from the compartment B. If desired more than one rinsing of the clothes may be carried out.

75 After the clothes have been rinsed they are

still left in the basket 7 for the drying operation. In Figure 1 I show a rheostat 32' placed in the electric circuit 33 to the motor 5. When the basket 7 is used for washing the clothes the arm 34 of the rheostat is placed in a position where the motor will rotate the basket approximately one hundred revolutions per minute. When, however, the basket is used for drying purposes the arm 34 is moved for cutting out the resistance and for causing the motor to operate at a sufficient speed to rotate the basket approximately nine hundred revolutions per minute. When the basket is rotating at this speed the vane 17 may be locked by any means, so as to extend tangentially to the wall of the basket 7. The rods 20 15 will therefore hold the rollers 21 free from the cam 22. One way of locking the rods 20 against movement is to place pins (not shown) in openings 20', these pins contacting with the collars 25' on the rods 20 and holding the rods against 20 longitudinal movement.

After the clothes have been dried the basket 7 may be swung into the dotted line position shown in Figure 1 upon freeing the bolts 14 from the projections 13. The cover 9 may now be removed and this will give access to the clothes which also may be removed. The operator may now place a new batch of clothes in the basket and again swing the basket into operative position and secure it in place by the bolts 14.

If desired the same washing fluid may be used for the second batch of clothes, and to this end I provide a water pump 35 operated by a shaft 36 connected to the motor 5. A clutch mechanism indicated generally at 37 connects the shaft 36 with the shaft of the motor only when it is desired to use the pump 35. The pump sucks the cleaning fluid from the compartment A by means of a pipe 38 and forces this liquid through a pipe 39 which communicates with the compartment B. If it is desired to drain the fluid from the compartment A and to discharge this fluid, a valve 40 in the pipe 39 is closed and the valve 41 in the discharge pipe 42 is opened. It is obvious that any other means for taking care 45 of the fluid in the compartment A may be used without departing from the spirit and scope of the invention.

It will be noted that a vacuum is created behind each vane except the one passing the partition 15, and that fluid is sucked from the basket to fill these vacuum spaces rather than from the space between the basket and the tub. The water in the basket and in the tub has a tendency to move outwardly during the rotation of the basket, 55 due to centrifugal force. Therefore, the water in the basket will flow outwardly to fill the vacuum spaces rather than the water between the basket and the tub filling the space. It has also been mentioned that the gradually reducing passageway 16 forces the liquid into the basket. In this way a flow of fluid is maintained through the basket for washing purposes.

Another feature of the invention is the movable clothes container that can be moved toward the open portion of the compartment to facilitate the removing of clothes from the container or the placing of additional clothes in the container. Any means for permitting this movement will suffice.

While I have shown only the preferred form of the invention, it should be understood that various changes or modifications may be made within the scope of the appended claim without departing from the spirit of the invention.

I claim:

A washer and drier comprising a tub, a frame extending into the tub from the top, a perforated clothes container vertically supported and horizontally pivoted in the frame and having a top that can be opened, means for locking the container to the frame, and means for rotatably supporting the frame, means for rotating the

frame and container as a unit, said container being swingable on its pivot into a tilting position in the frame when the locking means frees the container, whereby articles may be readily inserted in the container or removed therefrom through 5 the open top of the container.
